UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

957,402.

Specification of Letters Patent. Patented May 10, 1910.

Application filed December 12, 1909. Serial No. 532,601.

To all whom it may concern:

Be it known that I, CLIO B. YAW, citizen of the United States, and resident of Arlington, in the county of Hudson and State 5 of New Jersey, have invented certain new and useful Improvements in Type-Writing Machines, of which the following is a specification.

My invention relates to typewriting machines and more particularly to means whereby labels or small work sheets may be efficiently handled and properly held in position in the machine.

One object of my invention is to provide 15 simple and efficient means of the character specified.

A further object of my invention is to provide an auxiliary device which is in the nature of an attachment adapted to be 20 readily applied to or detached from existing forms of typewriting machines without modifying, or materially modifying, the structural features of said machines as they now exist and to employ said attachment in 25 combination with existing parts of a typewriting machine to efficiently handle, guide and feed labels or other like small work sheets without the necessity of providing a special machine for this purpose.

To the above and other ends, my invention consists in the features of construction, arrangements of parts and combinations of devices to be hereinafter described and particularly pointed out in the appended claims.

In the accompanying drawings wherein like reference characters designate corresponding parts in the various views, Figure 1 is a fragmentary plan view showing a portion of the carriage of a No. 10 Remington 40 machine embodying my invention. Fig. 2 is a detail isometric view of the frame and the auxiliary paper feed roller carried thereby. Fig. 3 is an enlarged detail vertical sectional view showing a portion of the carriage embodying my invention, together with some of the associated parts, the section being taken on the line $x-x$ of Fig. 1 and as seen when looking in the direction of the arrow at said line. Fig. 4 is a detail 45 fragmentary front view showing the platen, auxiliary paper feed roller and the usual indicator employed in the No. 10 Remington machine. This view illustrates a label in position in the machine for writing. Fig. 5 is a detail perspective view of one of the col-

lars 38 secured in position and by which the detachable frame may be connected to the rock shaft 27.

While I have shown my invention in the present instance embodied in a No. 10 Remington machine, it should be understood that the invention may be embodied in other styles of typewriting machines.

The platen frame or carriage comprises end plates 1 connected by cross bars 2 and 3. 65 A platen shaft 4 is mounted in bearings in the end plates and a cylindrical platen 5 is fixed to the shaft in the usual manner. A paper apron 6 which may be supported in the usual manner is shown in Fig. 1, the 70 paper apron directing work sheets from the rear to the front of the platen. Main paper feed rollers 7 and 8 are mounted on shafts 9 and 10, respectively, carried by yoke-like supporting members 11 pivoted at 12 to forwardly projecting arms 13 of angular supporting and cast-off levers 14 pivoted at 15. The angular levers have depending arms 16 to which the rear ends of contractile springs 17 are connected, the forward ends of said 80 springs being connected to pins 18 carried by the cross bar 3. A paper table support 19 is carried by the cross bar 2, the forward end portion of said support being provided with pivot-like projections 20 received in loops 85 or bearings 21 secured to the bottom of the paper table 22. The paper table is thus pivotally connected at 20-21 to swing on its support 19. A spring catch 23 is secured to and projects from the bottom of the paper 90 table and is provided with an engaging portion 24 which cooperates with the rear end portion 25 of the support to hold the paper table in normal position. Pressure exerted upwardly on the rear end of the paper table 95 forces the free end of the spring upwardly to disengage it from the engaging portion 25 of the support, thus freeing the spring catch and enabling the paper table to swing forwardly at the upper end thereof. A stop 100 26 projects downwardly from the bottom of the paper table and cooperates with the support 19 to limit the downward movement of the paper table around its pivotal support. A rock shaft 27 is mounted to turn in bearing openings in the end plates 1 of the carriage and has a restoring spring 28 surrounding it. One end of this spring is connected at 29 (see Fig. 1) to a hub 30 of a release key or finger piece 31, the opposite end 105

110

of the spring being connected at 32 to the left-hand end plate 1 in order to exert a pressure to turn the rock shaft 27 in the direction of the arrow in Fig. 3. The rock shaft 5 is provided with collars 33 which have depending fingers 33^a, which fingers coöperate with upwardly extending arms 34 on the angular levers 14. It will be understood therefore that when the finger piece 31 is moved 10 rearwardly, the fingers 33^a will coöperate with the upright arms 34 of the angular levers 14, thus turning said levers to lower the yokes 11 and the main paper feed rollers 7 and 8. The feed rollers will thus be moved 15 away from the platen to inoperative position, and when pressure on the finger piece 31 is released the feed rollers will be moved to operative position by the springs 17, and the spring 28 will restore the release shaft 20 27 and the finger piece 31 to normal position.

An indicator 35 is secured to the frame of the machine in position to guide the work sheet 36 near the printing point and to permit the upwardly and rearwardly striking type bars 37 to effect an imprint at the printing point through an opening in the member 35 as indicated in Fig. 4 by the letter "A".

The features thus far described constitute 30 parts of the No. 10 Remington machine and further detailed description thereof is deemed unnecessary.

In accordance with my present invention I provide two collars 38 upon the rock shaft 27, one of the collars being shown in detail in Fig. 5. These collars are adapted to be moved to different positions along the rock shaft 27 and to be adjusted to different positions around the shaft. A set screw 39 is 40 received in a tapped opening and each of the collars is adapted to bear at its inner end against the rock shaft 27 to secure the collar in its adjusted position on the shaft. The formation of these collars is best shown 45 in the detail view of one of these collars represented in Fig. 5 from which it will be seen that they each comprise an angular portion 40, formed by three side walls thereof, and a slotted portion 41. The angular portion 50 of each collar is of a size to be received in a corresponding angular open-mouthed opening 42 of a frame 43 shown in detail in Fig. 2. The engaging portions of the frame are likewise received in the slots 41 in order to 55 prevent a shifting movement of the frame longitudinally of the platen. The frame 43 comprises side arms 44 curved to correspond substantially to the curvature of the platen as shown in Fig. 3. These curved side arms 60 are united by a cross bar 45 to form a rigid rectangular frame and a paper feed roller 46 is formed with pivots 47 which are received in bearing openings in the forward ends of the arms 44. The frame when in 65 position is situated above the platen and ex-

tends from the rock shaft 27 in the rear of the platen to the forward side thereof so that the roller 46 will be situated just above and as close to the printing line (indicated by the dotted line *a* in Figs. 3 and 4) as the types and indicator 35 will permit. The frame 43 is positioned about centrally of the platen so that the feed roller 46 which is co-extensive with the width of the frame is likewise located centrally of the platen. The frame 43 is, by the connecting devices previously described, detachably and rigidly connected with the rock-shaft 27 so that the frame may be attached to or detached from the machine when desired. When the frame 70 is in place on the rock shaft said frame is rigidly connected to the shaft so that the pressure of the restoring spring 28 is effective through the shaft and frame 43 to press the auxiliary paper feed roller 46 against the work sheet above the printing line as indicated in Fig. 3. From an inspection of Fig. 3 it will also be seen that when the frame 43 is in place in the machine, the lower edge of the paper table 22 is situated 80 above the rear connecting ends of the side arms 44 so that the frame can not be moved upwardly at the rear end thereof to disengage it from the rock shaft 27. When, however, the upper end of the paper table is 85 swung forwardly the lower end 48 of the table is moved out of coöperative relation with the connecting portions 49 of the frame 43 so as to permit the frame to be moved upwardly to disengage it from the rock shaft 90 100 27 or the connecting devices or sleeves carried thereby.

By this construction small labels 36 may be introduced downwardly beneath the spring-pressed auxiliary paper feed roller 46 and between the member 35 and the platen, as indicated in Figs. 3 and 4. The grip of the auxiliary paper feed roller against the label is sufficient to retain it in place and the guide and indicator 35 maintain the label 105 110 snug against the platen at and adjacent to the printing point so that the label may be properly held in position while the writing proceeds.

From the foregoing description it will be 115 understood that by my invention I have provided a simple and efficient construction and that the frame 43 is in the nature of an attachment which may be readily attached to or detached from a No. 10 Remington machine without modifying, or materially modifying, the structural features of said machine as it now exists.

By this construction small labels may be 125 readily inserted beneath the auxiliary feed roller 46 from the front of the machine as hereinbefore described. If larger or longer labels or sheets are employed they may be introduced from the rear of the platen and fed downwardly between the two side arms 130

44 of the frame. When the machine is intended to be employed for ordinary work and is not to be used as a label writing machine, the frame 43 may be detached from 5 position and the operator may proceed to use the machine in the ordinary manner.

It will be understood from the foregoing description that I am enabled by my invention to convert the ordinary No. 10 Remington machine into a label writing machine and that it is unnecessary to provide a special machine for this work.

Various changes may be made without departing from the spirit and scope of my 15 invention.

What I claim as new and desire to secure by Letters Patent, is:—

1. In a front-strike typewriting machine, the combination of a spring-pressed frame 20 carrying a feed roller which extends longitudinally of the platen above the printing line, and throughout a substantial distance longitudinally of the platen, said frame comprising connected parallel side arms which 25 extend over the platen, and means for readily affording a detachment of said frame when desired.

2. In a front-strike typewriting machine, the combination of a platen, a rectangular 30 frame having curved side arms which extend over the platen, a paper feed roller carried by and extending between the side arms of said frame and situated above the printing line, spring-pressed means coöperative with said frame for forcing the roller against the platen or the work sheet thereon, and means for detachably connecting said frame to said spring-pressed means.

3. In a front-strike typewriting machine, 40 the combination of a platen, a frame having side arms which extend over the platen, a roller between said side arms at the forward ends thereof, said roller being situated above the printing line centrally of the platen, a 45 pivoted device in the rear of the platen, and means for detachably connecting said frame to said pivoted device.

4. In a front-strike typewriting machine, the combination of a platen, a frame having 50 side arms which extend over the platen, a roller between said side arms at the forward ends thereof, said roller being situated above the printing line centrally of the platen, a rock shaft, and means for detachably connecting said frame to said rock shaft.

5. In a front-strike typewriting machine, the combination of a platen, a frame having 60 side arms which extend over the platen, a roller between said side arms at the forward ends thereof, said roller being situated above the printing line centrally of the platen, a spring-pressed rock shaft in the rear of the platen, and means for detachably connecting said frame to said rock shaft.

6. In a front-strike typewriting machine,

the combination of a platen, a spring-pressed rock shaft in the rear of the platen, a frame which extends over the platen, means for detachably connecting said frame to said shaft, a paper feed roller carried by 70 said frame at the front side thereof so that the said roller bears against the platen above the printing line, the spring for the rock shaft exerting a pressure through said shaft and frame to maintain the feed roller 75 under spring pressure against the platen or the work sheet thereon.

7. In a front-strike typewriting machine, the combination of a platen, a spring-pressed rock shaft, a rigid frame which extends over the platen, said frame comprising side arms and a cross bar, means for detachably fixing the rigid frame to said rock shaft, and a feed roller carried by 80 said frame at the forward side thereof so that 85 the roller will press against the front side of the platen or the paper thereon above the printing line.

8. In a front-strike typewriting machine, the combination of a platen; a spring-pressed rock shaft arranged in the rear of 90 the platen; a frame comprising curved side arms that extend over the platen fore and aft of the machine, and a cross-bar that connects said side arms; a feed roller carried by 95 and extending between said side arms at the front ends thereof, said roller being situated above the printing line and centrally of the platen; and means for detachably fixing the frame to said shaft.

9. In a front-strike typewriting machine, the combination of a platen; a spring-pressed rock shaft arranged in the rear of 100 the platen; a frame comprising curved side arms that extend over the platen fore and 105 aft of the machine, and a cross bar that connects said side arms; a feed roller carried by and extending between said side arms at the front ends thereof, said roller being situated above the printing line and centrally 110 of the platen; and means for detachably fixing the frame to said shaft, said last mentioned means comprising angular portions on the shaft and open-mouthed corresponding angular openings formed in said 115 side arms for detachably engaging the angular portions on the shaft.

10. In a front-strike typewriting machine, the combination of a platen; a spring-pressed rock shaft arranged in the rear of 120 the platen; a frame comprising curved side arms that extend over the platen fore and aft of the machine, and a cross bar that connects said side arms; a feed roller carried by 125 and extending between said side arms at the front ends thereof, said roller being situated above the printing line and centrally of the platen; and means for detachably fixing the frame to said shaft, said last mentioned means comprising adjustable 130

angular faced collars carried by said rock shaft, and open-mouthed corresponding angular openings formed in said side arms to detachably engage the angular faced collars, 5 whereby said frame may be connected to turn with the shaft and a ready removal of the frame may be effected when desired.

11. In a front-strike typewriting machine, the combination of a platen; a spring 10 pressed rock shaft arranged in the rear of the platen; a frame comprising curved side arms that extend over the platen fore and aft of the machine, and a cross bar that connects said side arms; a feed roller carried by and extending between said side arms at the front ends thereof, said roller being situated above the printing line and centrally of the platen; and means for detachably fixing the frame to said shaft, said 15 last mentioned means comprising angular portions on the shaft and open-mouthed corresponding angular openings formed in said side arms for detachably engaging the angular portions on the shaft, said angular 20 portions being slotted to receive the side arms and prevent a movement of the frame longitudinally of the platen.

12. In a front-strike typewriting machine, the combination of a platen; a spring- 30 pressed rock shaft arranged in the rear of the platen; a frame comprising curved side arms that extend over the platen fore and aft of the machine, and a cross bar that connects said side arms; a feed roller carried 35 by and extending between said side arms at the front ends thereof, said roller being situated above the printing line and centrally of the platen; and means for detachably fixing the frame to said shaft, said last mentioned means comprising adjustable angular-faced collars carried by said rock shaft, 40 and open-mouthed corresponding angular openings formed in said side arms to detachably engage the angular faced collars, 45 whereby said frame may be caused to turn with the shaft and a ready removal of the frame may be effected when desired, said collars being likewise slotted to receive the side arms and prevent a movement of the 50 frame longitudinally of the platen.

13. In a front-strike typewriting machine, the combination of a platen, paper feed rollers, a rock shaft, means controlled by said rock shaft for releasing said feed rollers, an 55 auxiliary paper feed device, and means for detachably connecting said auxiliary feed device with said rock shaft.

14. In a front-strike typewriting machine, the combination of a platen, paper feed rollers, a rock shaft, means controlled by said rock shaft for releasing said feed rollers, and an auxiliary paper feed device at the 60 front of the platen above the printing line, said auxiliary paper feed device being carried by said spring pressed rock shaft.

15. In a front-strike typewriting machine, the combination of a platen, paper feed rollers, a rock shaft, means controlled by said rock shaft for releasing said feed rollers, and an auxiliary paper feed roller situated 70 at the front of the platen above the printing line, said auxiliary paper feed roller being carried by said spring-pressed rock shaft and pressed thereby against the platen or the paper thereon. 75

16. In a front-strike typewriting machine, the combination of a platen, paper feed rollers, a rock shaft, means controlled by said rock shaft for releasing said feed rollers, an auxiliary paper feed roller situated at the 80 front of the platen above the printing line, said auxiliary paper feed roller being carried by said spring-pressed rock shaft and pressed thereby against the platen or the paper thereon, and means whereby the said auxiliary feed roller may be readily detached from said rock shaft. 85

17. In a front-strike typewriting machine, the combination of a platen, paper feed rollers beneath the platen, a spring-pressed rock 90 shaft, means controlled by said rock shaft for releasing said feed rollers, a frame situated above the platen, an auxiliary feed roller carried by said frame, and means for rigidly connecting the frame to said rock 95 shaft, whereby the spring of the rock shaft is exerted through said shaft and frame to cause the auxiliary feed roller to bear against the platen or the paper thereon.

18. In a front-strike typewriting machine, the combination of a platen, paper feed rollers beneath the platen, a spring-pressed rock shaft, means controlled by said rock shaft for releasing said feed rollers, a frame situated above the platen, an auxiliary feed 100 roller carried by said frame, and means for detachably and rigidly connecting the frame to turn with said rock shaft, whereby the spring of the rock shaft is exerted through said shaft and frame to cause the auxiliary 110 feed roller to bear against the platen or the paper thereon and whereby the frame and auxiliary feed roller may be readily detached when desired. 105

19. In a front-strike typewriting machine, the combination of a platen, main paper feed devices arranged below the platen, auxiliary paper feed devices arranged above the printing line, spring restored means for releasing said main paper feed devices, and 120 means for connecting said auxiliary paper feed device with said releasing means so that the restoring spring for the latter will exert a pressure to normally maintain the auxiliary paper feed device against the 125 platen or the paper thereon.

20. In a typewriting machine, the combination of a platen, a paper table, a detachable paper feed device co-operative with the platen, and means whereby the paper table is 130

rendered effective to prevent an accidental detachment of the paper feed device.

21. In a typewriting machine, the combination of a platen, a detachably mounted support, a paper feed device carried by said support, and a paper table mounted for swinging movement into and out of co-operative relation with said support to prevent the detachment of the support or to enable it

10 to be detached.

22. In a typewriting machine, the combination of a platen, a rock shaft, a frame detachably mounted on said rock shaft, a paper feed device carried by said frame, and a 15 paper table mounted for swinging movement into and out of co-operative relation with said frame to prevent the detachment of said frame or to enable it to be detached.

23. In a front-strike typewriting machine, 20 the combination of a platen, a rock shaft in

the rear of the platen, a frame detachably mounted on but rigidly fixed to turn with said rock shaft, said frame extending above the platen from the rear to the front side thereof, a paper feed roller carried by said frame at the forward side thereof, and a paper table mounted for swinging movement into and out of co-operative relation with said frame to prevent the detachment of said frame or to enable it to be detached from 25 the rock shaft with the feed roller carried thereby.

Signed at the borough of Manhattan, city of New York, in the county of New York, and State of New York, this 10th day of 30 Dec. A. D. 1909.
